UNITED STATES PATENT OFFICE.

JOSEPH E. RIDDER, OF NEW YORK, N. Y., ASSIGNEE TO INTERNATIONAL TYPESETTING
MACHINE COMPANY, OF NEW YORK, N. Y., A CORPORATION OF NEW YORK.

MOLD.

1,124,953.

Specification of Letters Patent. Patented Jan. 12, 1915.

Application filed June 20, 1912. Serial No. 704,917.

To all whom it may concern:

Be it known that I, JOSEPH E. RIDDER, a citizen of the United States, residing at New York, in the county of New York and State of New York, have invented new and useful Improvements in a Mold, of which the following is a specification.

The present invention relates to improvements in linotype machines and more particularly to the mold used in casting the lines of type, and the primary object of the present invention is to provide an improved mold of this character which enables the same to be opened and the liners which serve 10 to gage the length of the line and the body size thereof to be readily removed or inserted, the mold cap in the preferred embodiment of the invention being pivoted or swiveled at one end whereby it may be 15 quickly and easily swung into open and closed positions with respect to the mold, thereby facilitating insertion and removal of the liners without the necessity of detaching the cap, and a pivoted or swiveled screw 20 25 serves to clamp the free end of the cap.

Another object of the invention is to provide improved means for mounting the mold on and securing it to the mold disk or carrier whereby the mold is positioned accurately and securely with respect thereto.

To these and other ends, the invention consists in certain improvements, and combinations and arrangements of parts, all as will be hereinafter more fully described, 30 35 the novel features being pointed out particularly in the claims at the end of the specification.

In the accompanying drawing:—Figure 1 is a perspective view of a mold wheel or carrier equipped with two molds constructed in accordance with the preferred embodiment of the present invention, the cap of one of the molds being shown swung into open position to render the liners accessible; Fig. 2 is a face view of a portion of the mold disk or carrier showing the mold in closed position, portions being illustrated in section; Fig. 3 represents a top plan view of the mold and the mold disk or carrier wheel, the mold being in closed condition; Fig. 4 represents a section on the line 4—4 of Fig. 2; Fig. 5 is a perspective view of one of the liners.

Similar parts are designated by the same reference characters in the several views.

The present invention is applicable generally to molds and mold carriers of different types although it is especially adapted to molds of the type used by the well known linotype machines for the casting of slugs or lines of type. The present invention moreover is especially adapted for use in connection with a mold disk or wheel of the construction described fully in a concurrent application for Letters Patent by Thomas S. Homans, Serial No. 704,441, filed June 18, 1912, and I have shown the same so applied in the accompanying drawing and such a construction will be hereinafter referred to in detail. It is to be understood, however, that the invention is not restricted to the particular construction shown and described, as equivalent constructions may be used to accomplish the purposes and results of the present invention.

In the present instance the mold carrier is in the form of a disk 1 which is similar to that used by the well known linotype machine, it being mounted to rotate on a shaft 2 and is driven by the gear 3 which is arranged peripherally of the disk. A suitable number of lugs or projections 4 extend laterally from the face of the disk and serve to accurately position the molds and to secure them to the disk, these lugs or projections being offset with respect to the plane of the peripheral gear teeth whereby the mold and all of its parts are out of the plane of the driving and supporting means for the disk. The disk may carry any suitable number of molds, two molds being shown on the disk in the present instance, the molds being of duplicate construction. Each mold comprises a body 5 which is interposed between the opposed surfaces 6 of a pair of lugs or projections on the disk, the ends of the mold body being fitted to abut properly against these opposed surfaces of the lugs or projections whereby the mold body will be positioned in a longitudinal direction with respect to the mold disk. In the present instance, the mold body is shown provided with ledges 7 which constitute a matrix keeper for positioning the line of matrices properly before the mold for the casting operation as well understood. The mold body is also provided in the present instance with extensions 8 which project longitudinally beyond its ends, and the under surfaces of these extensions are properly

finished to seat upon the surfaces 9 of the lugs or projections, these surfaces 9 being in alignment and are so finished or located with reference to the disk that when the 5 tensions of the mold body rest thereon the mold will be positioned properly with respect to the center or axis of the disk. The lugs or projections 4 therefore serve to position the mold in two directions, that is to say, in a direction lengthwise of the mold and in a direction radially of the axis of the disk or mold carrier. The mold is also provided with a cap 10 and liners 11 of different thicknesses and lengths may be interposed between the cap and body to determine the body size of the lines of type or slugs as well as the length of the lines of type, and in order to facilitate and insure proper positioning of the liners, dowel pins 15 or projections 12 may be provided, those shown being fitted in the upper face of the mold body and are adapted to coöperate with apertures 13 in the respective liners. The present invention provides means for 25 pivotally connecting the cap to the body of the mold and in the preferred construction such means also serves to clamp the cap, liners and body together and to secure these parts to the respective mold-supporting and 30 positioning lug or projection. In the present instance, a clamping screw 14 serves these purposes, it extending through an aperture 15 in one end of the mold cap, an open-ended slot 16 in the liner for this end 35 of the mold, and an aperture 17 in the respective extension 8 of the mold body and is tapped into the respective lug or projection 4. When this screw is tightened, it clamps together the mold cap, the body and 40 the interposed liner at such end of the mold as well as to secure the parts of the mold named to the respective mold-supporting and positioning lug, and loosening of this screw relieves the clamping action upon the 45 mold parts, enabling the mold cap to be swung laterally about the screw as a pivot or axis, rendering the inner end of the respective liner accessible, and this liner may then be lifted to disengage it from the 50 respective dowel pin and then withdrawn, withdrawal of the liner being permitted by using the open-ended slot 16. Another liner of selected dimensions may then be inserted and the mold parts closed and 55 clamped together.

The opposite end of the mold is provided with clamping means which secures together the mold parts and also secures the mold to the respective mold-positioning and supporting lug. In the preferred embodiment of the invention, a swiveled screw or bolt is used, that shown embodying a shank 18 which is pivoted on a pin 19, the latter being mounted in the lug and forming an 60 axis about which the bolt may swing to and 65

from an operative position, the lug or projection to which the swiveled bolt or screw is attached being provided with a slot 20 to accommodate the same. The free end of the screw or bolt is provided with a threaded stem 21 and a coöperating nut 22, and a slot 23 extends inwardly from the respective ends of the mold body, cap and liner, enabling the bolt to assume a position with its axis transverse to the length of the mold and with the nut bearing on the cap. When the nut is tightened, this end of the mold is securely clamped in closed condition and the mold is secured to the respective mold-positioning and supporting lug. However, by loosening the nut, the clamping action on this end of the mold is relieved and when the swiveled bolt is swung out of the slot 23, the mold cap may be swung laterally about the screw or pivot 14 as a center or axis. When the mold is open in this manner, the liners are readily accessible, although it will be observed that the parts of the mold are not detached and hence delay, due to loss or displacement of the parts, is avoided and the handling of the parts to make any desired changes of adjustment in the mold is greatly facilitated.

I claim as my invention:

1. In a machine of the linotype class, the combination with a mold disk, of a mold mounted thereon having a body and a cap coöperative therewith, and clamping devices for attaching said parts to the mold disk one of which may form an axis to swing the cap in relation to the body of the mold.

2. In a linotype machine, the combination with a mold disk, of a mold mounted thereon having a body, a cap coöperative therewith, and a clamping device secured to the mold disk and forming an axis at one end of the mold about which the cap and body thereof are relatively movable to open and close the mold.

3. In a linotype machine, the combination with a mold disk, of a mold mounted thereon comprising a body, a cap, liners for spacing the distance between them, a pivot connecting the body and cap at one end of the mold to the mold disk, and a clamping device for the body and cap at the opposite end of the mold.

4. In a linotype machine, the combination with a mold disk, of a mold mounted thereon having a body, a cap coöperative therewith, means pivotally connecting the body and cap at one end of the mold to the mold disk to permit opening of the cap and for positioning the body and cap, and clamping means connecting the body and cap at the opposite end of the mold.

5. In a linotype machine, the combination with a mold disk, of a mold mounted thereon having a body, a cap coöperative

therewith, a combined pivot and clamping screw connecting the body and cap at one end of the mold to the mold disk, and clamping means connecting the body and cap at the opposite end of the mold.

6. In a linotype machine, a mold having a body, a cap coöperative therewith, means pivotally connecting the body and cap at one end of the mold to permit opening of the latter and for positioning the body and cap, and a swiveled clamping device coöperative with the body and cap at the opposite end of the mold.

7. In a linotype machine, the combination of a mold carrier provided with mold-supporting and positioning projections, a mold having a body provided with longitudinal supporting and positioning extensions, and a cap coöperative therewith, and clamping devices coöperative with said body and cap toward the ends of the mold for securing the body and cap to said projections.

8. In a linotype machine, the combination of a mold carrier provided with a pair of projections having opposed and also

aligned surfaces, and a mold having a body provided with end surfaces coöperative with the opposed surfaces of said projections and longitudinal extensions coöperative with the aligned surfaces of said projections, and means securing the mold body and cap together and to said projections.

9. In a linotype machine, the combination of a mold carrier provided with mold positioning and supporting projections, and a mold comprising a body, a cap coöperative therewith, means for securing the body and cap together and to one of said projections at one end of the mold and pivotally mounting the cap, and clamping means coöperative with the body and cap and another of said projections at the opposite end of the mold.

In testimony whereof I have hereunto set my hand in presence of two subscribing witnesses.

JOSEPH E. RIDDER.
